(57) **CLAIM**

We claim the ornamental design for a side of file bin, as shown and described.

DESCRIPTION

FIG. 1 is a top perspective view of a side of a file bin showing our new design;

FIG. 2 is a front elevational view thereof;

FIG. 3 is a top perspective view of an embodiment of FIG. 1 thereof;

FIG. 4 is a front elevational view of FIG. 3;

FIG. 5 is a top perspective view of a second embodiment of FIG. 1 thereof; and,

FIG. 6 is a front elevational view of FIG. 5.

The ornamental design which is claimed is shown in solid lines in the drawings. The broken lines in the drawings are for illustrative purposes only and form no part of the claimed design.
